UNITED STATES PATENT OFFICE.

JOHN E. BELL, OF BROOKLYN, NEW YORK, ASSIGNOR TO SINCLAIR REFINING COMPANY, OF CHICAGO, ILLINOIS. A CORPORATION OF MAINE.

METHOD AND APPARATUS FOR CRACKING OILS UNDER PRESSURE.

Application filed April 1, 1924 Serial No. 703,339.

To all whom it may concern:

Be it known that I, JOHN E. BELL, a citizen of the United States, residing at Brooklyn, in the county of Kings, State of New York, have invented certain new and useful Improvements in Methods and Apparatus for Cracking Oils Under Pressure; and I do hereby declare the following to be a full, clear, and exact description of the invention, such as will enable others skilled in the art to which it appertains to make and use the same.

This invention relates to improvements in the construction and operation of pressure stills for cracking heavier hydrocarbon oils for the production of lighter hydrocarbon oils therefrom.

In the cracking of heavier hydrocarbon oils in pressure stills, the pressure is controlled either by release of fixed gas at a point beyond the condenser or by means of a pressure regulating and reducing valve interposed between the pressure still and the condenser. The regulation of the pressure in either of these ways requires the attendance of an operator and the adjustment of valves to maintain a substantially uniform pressure under varying conditions of operation.

The present invention provides a new and improved method and means for controlling and regulating the pressure of pressure stills. According to the present invention, the pressure still is provided with a fixed orifice from which the vapors and gases can escape at a substantially constant rate, and the vapors from the pressure still, before reaching such discharge orifice, are subjected to partial condensation, and this partial condensation is regulated and varied to take care of fluctuations of operation and to maintain approximately constant pressure in the still.

The pressure stills themselves with which the invention is combined, or in which the method of the invention is carried out, may vary in their construction. It may be a pressure still of the shell type, or it may be a tubular pressure still. In case of a tubular still, the still may be one in which the oil is circulated from a large supply tank or drum through heating tubes and back to the main supply tank, or it may be a still in which the oil is passed through the heating tubes in a single pass. The invention is of

more or less general application in so far as the construction of the pressure still is concerned.

Pressure stills are commonly provided with a reflux tower so connected and arranged as to subject the vapors from the pressure still to a refluxing operation so as to condense and return the heavier vapors. The present invention is of special application and advantage in connection with pressure stills which are provided with such reflux towers, although the invention, in its broader and more general applications, is not limited to the use of a reflux tower or to the return of the reflux or condensed vapors to the pressure still.

In pressure stills where a reflux tower is provided, I also provide one or more additional towers which are adapted to be maintained at still pressure, and I provide such additional tower or towers with a fixed orifice outlet and with variable condensing means so that a regulated amount of the vapors can be condensed therein. By regulating the condensation in this way, a regulated flow of vapors is provided which is approximately constant in amount through the fixed outlet.

The present invention accordingly involves a partial and regulated condensation of the vapors while they are maintained under the same pressure as that in the pressure still, or in the vaporizing chamber of such still, and a subsequent condensation of the remaining vapors under a lower pressure, which may be atmospheric or a predetermined pressure higher than atmospheric.

The fixed orifice, or orifices, in case more than one is used, may vary somewhat in their construction but in general they should be so constructed as to permit a substantially constant outflow of vapors therethrough and to offer a sufficient resistance to such flow to maintain the desired pressure in the pressure still. The orifice may be one which is adjustable, and which, when once adjusted, can be left without further adjustment or regulation during the pressure still run.

With such a fixed orifice as the means of escape of the high pressure vapors from the pressure still, is it evident that increase in pressure in the still will bring about a corresponding outflow of vapors. According to the present invention, however, if the

- pressure increases in the still, the condensing effect upon the vapors is increased, so that an increased amount of the vapors is condensed, and the pressure thereby reduced.
- 5 The operation of the pressure still is thus regulated and controlled without regulation and control of the outlet from the still; and a substantially constant rate of outflow through a fixed orifice outlet is obtained
- 10 while regulating the pressure within the still by a variable condensation of the vapors before they escape through the fixed outlet.

15 The regulations of the condensation of the vapors, according to the present invention, can be effected in various ways. For example, one advantageous method of regulation is to provide a second tower in addition to the usual reflux tower and to circulate

20 through this second tower a regulated amount of a cooling fluid. By regulating the amount of the cooling fluid so circulated, the cooling and condensing effect can be regulated. The cooling fluid may advantageously be cold oil which is to be fed into

25 the pressure still as charging stock or a part only of the still feed may be employed as the cooling fluid. Instead of employing oil, cold water or other liquid can be em-

30 ployed and can be circulated in regulated amount through the tower for regulating the condensation of the vapors.

35 In the practical carrying out of the invention, the regulation of the condensation can be controlled automatically by a pressure regulator acting upon the cooling fluid circulated in heat interchanging relation with the vapors. As the pressure in the still increases, such a regulator will cause an

40 increased amount of the cooling liquid to flow through the tower and a correspondingly increased condensation of such vapor; while if the pressure in the still decreases, the flow of cooling liquid will be reduced

45 and the amount of vapors condensed will be correspondingly reduced.

50 The condenser construction for subjecting the vapors to the condensing action of the cooling liquid can be varied, but in general, the construction should be such as to present a relatively large surface of heat interchanged between the vapors and the cooling liquid.

55 The condenser may be of tubular construction with the cooling liquid flowing through tubes or it may be of multi-whirl construction with the vapors in the shell space coming in at the bottom and going out at the top, and the cooling liquid circulating

60 through small cooling pipes entering at the top and flowing out at the bottom. A tower in which the vapors are directly contacted with the cooling medium, for example, a tower in which cool oil is introduced into

65 the vapors may be employed.

Where the pressure still is provided with a reflux tower, the condensate from the variable condenser will be of intermediate character, lighter than the reflux from the reflux tower and heavier than the final condensate. This intermediate fraction or cut may be returned to the pressure still or it may be separately drawn out and treated in a separate pressure still or it may be used for some other purpose.

75 Where gas oil is the charging stock in a pressure still and gasoline or pressure distillate is the product desired in the final condenser the intermediate fraction or cut from the variable condenser will be of a kerosene-like character and can be used where an oil of such intermediate composition is desired.

80 The improved regulation of the present invention can accordingly be embodied and combined in a pressure still and in the operation of such a still in such a way as to give a fractional condensation of the vapors from the still, with the obtaining of one or more intermediate fractions in addition to

85 the final gasoline or pressure distillate fraction. The heavier vapors may be thus be returned directly to the pressure still from the reflux tower while the lighter vapors, including the lighter gas oil and kerosene

90 constituent as well as the gasoline constituents can be fractionally condensed and recovered as fractions, for example, by separating the kerosene fraction in the variable condenser and the gasoline fraction in the

95 final condenser at a lower pressure. By operating in this way, only heavier oil is present in the pressure still, the light constituents being carried over to the variable condenser and separately condensed.

100 Where the cooling of the variable condenser is effected by cold oil, the oil will be preheated, and this oil may advantageously be that which is supplied as charging stock to the still, so that the heat absorbed in the condenser will be made available to assist in the cracking operation. This preheated oil may advantageously be supplied, or part of it supplied to the top of the reflux tower and permitted to intermingle with the vapors in such tower to promote the refluxing operation. The lighter constituents of such feed will be vaporized and will pass over with the vapors from the pressure still to the variable condenser, and the heavier vapors will be condensed in the variable condenser, while the lighter vapors will pass through the fixed orifice to the final condenser. The introduction of the feed in this way not only preheats the feed but also fractionates it and separates it into a heavier charging stock for the pressure still and lighter constituents which are separately condensed either in the variable condenser as intermediate oil or in the final condenser as gasoline

or pressure distillate. Gasoline and kerosene constituents of the charging stock can thus be driven off and separately recovered without introducing them into the cracking still proper.

Where the same oil is circulated first through the variable condenser and then into the top of the reflux tower, any increase in the amount of oil circulating through the 10 variable condenser will likewise increase the amount of oil fed into the reflux tower. This will result in an increased condensing action in the variable condenser and an increased cooling action in the reflux tower 15 as well as an increase in the amount of oil fed to the still proper.

In the preferred practice of the invention, the pressure still is provided with a reflux tower through which the vapors from the 20 still are first passed, and the still is also provided with a second tower which will act as a variable condenser, in which the vapors will be subjected to a regulated condensation and from which the uncondensed 25 vapors will escape at a substantially constant rate through a fixed orifice or nozzle outlet. In such a still, the pressure will be regulated by regulating the condensation in the variable condenser, for example, by circulating a cooling fluid through a cooling coil 30 at a controlled rate, increasing the flow with pressure increase and decreasing the flow with pressure decrease. The flow of feed oil may be controlled by hand or automatically 35 by a pressure regulating valve acting upon the supply of cooling fluid.

The invention will be further described in connection with the accompanying drawings which illustrate, in a somewhat conventional and diagrammatic manner, four 40 pressure still constructions embodying the invention and adapted for the practice of the process of the invention. It will be understood, however, that the modifications so illustrated and described, are illustrative of the invention, and that the invention is not limited thereto.

In the accompanying drawings Figs. 1, 2, 3 and 4 illustrate diagrammatically and 50 partly in section three embodiments of the invention.

In the drawings the pressure still illustrated is of the general type and construction set forth in U. S. Letters Patent No. 55 1,285,200, granted November 19, 1918, to the Sinclair Refining Company upon an application of Edward W. Isom, but it will be understood that the invention is applicable to other pressure stills and may be combined therewith in a similar way and with the same or similar advantages.

In the accompanying drawings the same or corresponding parts are indicated by the same reference characters.

65 The pressure still illustrated comprises

the drum or bulk supply tank 5, the vertical heating tubes 6 located in the heating flue of the furnace 7, the pipe connections 8, 9 and 10 connecting the bulk supply tank with the top and bottom headers or manifolds, respectively, of the vertical heating tubes and the pump 11 for circulating the oil from the bulk supply tank through the heating tubes and back to the bulk supply tank.

70 Located above the pressure still is a reflux tower 13 connected with the vapor dome 12 of the bulk supply tank by a vapor line and having a return pipe 14 for returning the reflux to the bulk supply tank. The reflux tower is shown as of common baffle construction. The bulk supply tank 5 is shown with an outlet 15 for the withdrawal of tar.

75 The vapor outlet 16 from the top of the reflux tower passes to the bottom of a variable condenser 20 having a cooling coil 80 therein whereby a regulated amount of the vapors can be condensed. The variable condenser 20 has a fixed orifice outlet 21, conventionally shown, but of a construction such that a sufficient resistance will be provided to the escape of vapors therethrough to maintain the necessary or desired pressure in the pressure still. A valve controlled by-pass 31 is provided around the fixed orifice 85 to permit the free escape of vapors and gases in the event of excessive rise of pressure in the pressure still. This emergency bypass may be automatic in its action, acting upon a predetermined increase in pressure above that normally maintained in the 90 still, or it may be hand controlled.

95 The vapors and fixed gas escaping through the fixed orifice 21 pass through the vapor line 22 to the condenser shown conventionally at 23. The condensed vapors and uncondensed gas are collected in the receiver 24 from which the condensate or pressure distillate is drawn off through the valve controlled pipe 25 and the fixed gas and uncondensed vapors through the valve controlled outlet pipe 26. The pressure maintained on the condenser and receiver may be approximately atmospheric or may be a predetermined pressure between still pressure and atmospheric.

100 In the construction illustrated in Fig. 1 the cooling coil 30 located in the variable condenser 20 is supplied with feed oil of the character which is charged into the pressure still. This feed oil is supplied 105 through the feed pipe 60 and a regulated amount circulated through the coil 30, the amount being regulated by the valve 32. In place of regulating the flow of oil by valve 32 by reference to the pressure gage 32^a, the flow of oil may be regulated by the pressure-actuated valve 32^b. After flowing 110 through the coil and being preheated therein, the oil then passes to the top of the reflux tower (the valves 33, 36 and 37 being open 115 120 125 130

- and the valve 38 closed) and enters the reflux tower at the top through the pipe 35; or by opening the valves 33 and 39, and closing the valve 36, the preheated oil will be discharged through the pipe 34 into the circulating stream of oil in the pipe 10. By opening the valves 38 and 37 and closing the valve 36, the feed oil can be fed without pre-heating into the top of the reflux tower 13.
- 10 A supplemental feed line 60^a permits the introduction of additional feed either to the top of the tower or to the circulating stream of oil. This line 60^a also permits the escape of oil after it has circulated through the variable condenser without introducing it into the pressure still, the valve 33 and the valve in the pipe 60^a being open, and the valves 36 and 39 being closed.
- 15 It will thus be seen that the construction illustrated in Fig. 1 provides for various methods of operation. The cold feed oil can be circulated through the coil 30 without entering the pressure still, or this preheated oil can be in part or in whole introduced into the pressure still either through the reflux tower or through the circulating line or in part through each. In addition, the feed oil can be independently supplied to the still.
- 20 30 In the operation of the apparatus illustrated in Fig. 1 the oil in the still will be rapidly circulated from the bulk supply tank 5 through the heating tubes and back to the bulk supply tank and the oil will thus be heated to a cracking temperature, while the pressure will be raised to that corresponding to the temperature of cracking. The vapors given off from the pressure still will be subjected to a refluxing operation in the tower 13 where they will come in contact with the feed oil introduced either cold or in a pre-heated state. The heavier constituents of the vapors from the still and the heavier portions of the feed will be returned to the pressure still. The uncondensed vapors from the still and the vaporized portions of the feed will pass over through the pipe 16 into the variable condenser 20 where they will be subjected to a regulated condensing operation. The contents from this variable condenser can be drawn out through the line 27 to a place of storage or of further use. The uncondensed vapors from the variable condenser will escape with reduction of pressure through the orifice 21 and the expanded vapors will then pass to the main condenser where the condensation of the gasolene or pressure distillate will take place.

- still. The regulation of the pressure is effected by regulation of the rate of condensation in the variable condenser 20. With increase in pressure, the rate of flow of the cooling fluid is increased so that the rate of condensation is increased, with resulting decrease in the pressure and decrease in the amount of vapors and gases which must escape from the still to maintain the desired pressure. When the pressure is thus reduced to the predetermined or desired pressure, the rate of flow of the cooling liquid will be regulated to maintain this rate of condensation.
- 135 Regulation of the condensation in this way, increasing it with increase in pressure in the still and vice versa, the operation is continued with substantially constant outflow of vapors through the fixed orifice and with control of operation by increase and decrease of flow of cooling liquid, and corresponding increase and decrease in the amount of vapors condensed, as the pressure increases or decreases in the still. It will be evident that this method of pressure control is independent of the manipulation of valves in the distillation system, and that the vapors escape unregulated and in approximately constant amount through the fixed orifice, the regulation being preliminarily effected by regulated condensation under the pressure maintained in the still itself.
- 140 As an example of the operation of the apparatus, the orifice may be designed to permit the passage of 75% of the amount of vapors and gases normally produced by the pressure still under the usual conditions of operation. If we take the total production of vapors as 100 units, then 75 units would pass through the orifice, and the desired equilibrium would be maintained by condensing 25 units in the variable condenser 20. If the rate of formation of vapors increased in the still to say 125 units, there would still be about 75 units passing through the fixed orifice and the remaining 50 units would be condensed in the variable condenser. If the amount of vapors increased to 150 units, the amount condensed would increase to 75 units while 75 units would still escape through the fixed orifice. If, on the other hand, the still production decreased to 75 units, this total production would pass through the fixed orifice and no condensation would be required in the variable condenser 20. It will be evident that the amount of vapors flowing from the reflux tower to the variable condenser is equal to the amount of vapor passing through the orifice 21 plus the amount condensed in the variable condenser.
- 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
- With the pressure still of the construction illustrated and using ordinary gas oil charging stock, the heavier vapors will be refluxed

to the still while a fraction or cut similar to kerosene can be drawn off from the variable condenser 27 and a final gasoline distillate or kerosene distillate can be recovered from the final condenser. While the intermediate or kerosene distillate may be returned to the pressure still, it is more advantageously subjected to a separate cracking operation by circulating it through a separate cracking coil maintained under a sufficient pressure and at an appropriate temperature for such lighter charging stock. This intermediate kerosene distillate may, for example, be treated with advantage in accordance with the vapor phase cracking process set forth in application, Serial No. 584711 of Edward W. Isom, filed August 28, 1922, and the products of such vapor phase cracking operation may be returned to the main pressure still.

The final condensation of the vapors passing the fixed orifice can be effected in condensers of various types. The fixed nozzle or orifice will cause the vapors passing therethrough to have a relatively high velocity. This velocity may be taken advantage of in a condenser in which the vapors are discharged as a jet into a body of condensate, for example, as described in U. S. applications Serial No. 470,790, filed May 19, 1921, Serial No. 472,990, filed May 27, 1921, Serial No. 479,796, filed June 23, 1921, Serial No. 657,177, filed August 13, 1923, Ser. No. 661,750, filed Sept. 10, 1923 which described apparatus and methods for the condensation of hydrocarbon vapors by injecting them into cooled bodies of liquid condensate. In the drawings, a conventional form of condenser is illustrated.

The fixed orifice illustrated in the drawing is shown as a restriction in the outlet pipe but, as above noted, this orifice may be adjustable so that, for example, if the still is to be operated with an increased rate of vapor formation, a fixed orifice of increased size may be provided by suitable adjustment, and the still then operated with a regulated fixed orifice adapted to the conditions of operation. When the fixed orifice has once been adjusted, the pressure control then becomes independent of any further adjustment of valves, connected with the pressure still, but the regulation is accomplished entirely by variable condensation of the vapors in the manner previously described, and a substantially constant pressure is maintained by varying the feed or cooling liquid in the variable condenser.

In the apparatus in Fig. 1, the feed or cooling oil for regulating the cooling and condensing action is accomplished by hand operated valves, but, as already pointed out, the regulation may be automatic in character. Figs. 2 and 3 show two types of apparatus with automatic control.

In Fig. 2 the variable condenser 20 is provided with a cooling coil 40 conventionally shown, and through which oil or other liquid is circulated. This cooling coil has inlet and outlet valves 42 and 43, but the primary control of the cooling liquid therethrough is by means of a pressure actuated valve conventionally shown at 44. In practice, this pressure control valve should be one which will withstand the pressure of the pressure still 70 on one side of the diaphragm or other actuating means and it should be sensitive to within a narrow pressure range above and below that which it is desired to maintain in the pressure still so that it will increase 75 the flow of cooling fluid through the coil with increase of pressure and decrease the flow with decrease of pressure. The connecting pipe 45 is shown as connecting the pressure regulating valve 44 with the interior of the 80 variable condenser 20 but by closing the valve in the pipe 45 and using the hand operated valves 42 and 43 the flow of oil or water or other cooling liquid can be manually controlled. 85

In the operation of the pressure still illustrated in Fig. 2 the feed may be introduced through the feed line 60 and the pipe 35 into the top of the reflux tower and a partial regulation of the operation of the still 90 can be effected by regulating the amount of the feed so introduced. The vapors from the reflux tower and while still under same pressure will then be subjected to a regulated condensation in the variable condenser 95 100 105 110 115 120 125 130 135 140 145 150 155 160 - which is regulated by a pressure actuated control 54 operated by a pressure regulator shown conventionally at 55, and connected through the pipe 57 with the vapor space 6 in the pressure still. The pressure regulator and variable speed motor and control are conventionally shown but they should be so constructed and related to the cooling liquid and construction of the cooling coil 10 that the increase in pressure in the pressure still will increase the speed in the motor and the rate of circulation of the cooling liquid so as to maintain an approximately constant pressure in the system and variable 15 condensation of vapors with variation in the amount of vapors produced in the pressure still.

In the construction illustrated in Fig. 4 20 the variable condenser 70 is a baffle tower, conventionally shown, through which cool oil is introduced directly into the vapors 25 therein. This cool oil is supplied to the top of the tower 70 through pipe 71, either from the feed pipe 60 or through pipe 72, and the flow of cooling oil is regulated by the 30 valves 74 or 74^a and 75. The condensate and revaporized cooling oil, after passing over the baffles in the tower and effecting partial and regulated condensation of the 35 vapors therein, leaves the tower through pipe 73, and may be discharged through the valve controlled pipe 76 (the valve 77 being closed) or may be discharged into the circulating stream of oil in the pipe 10 40 through pipe 34 (the valves 39 and 77 being open and the valve 76 closed). A supplemental valve controlled connection 78 permits the introduction of additional feed into the circulating stream of oil.

In the operation of the pressure still illustrated in Fig. 4, the feed may be introduced 45 through the feed line 60 and the pipe 35 into the top of the reflux tower 13 and a partial regulation of the operation of the still can be effected by regulating the amount of feed so introduced by valve 37. The vapors from the reflux tower, still under the same 50 pressure, will then be subjected to a regulated condensation in the variable condenser 70. The uncondensed vapors will escape 55 through the fixed orifice 21 and the variable condenser will be regulated, by regulation of the oil introduced through pipe 71, to condense the excess amount of vapors, in excess of the constant amount flowing 60 through the fixed orifice. The intermediate condensate escaping at 73 may be returned to the pressure still, or it may be treated in a separate pressure still, or subjected to any desired further treatment. The vapors 65 escaping through the fixed orifice pass through the pipe 22 to the condenser and receiver.

Feed oil from the line 60 may be introduced 70 into the variable condenser to effect

the regulated condensation therein, or a separate fraction, such as a part of the condenser distillate collecting in the receiver 24, may be returned through pipe 72 for this purpose. Where all or a part of the feed 70 oil to the pressure still is introduced through the variable condenser, the unvaporized feed oil and condensate may be returned to the circulating line of the still, or it may be introduced into the top of the reflux tower on 75 the still by means of a pump through suitable connections (not shown). Where a part of the condensed pressure distillate is employed to effect the regulated condensation in the variable condenser, the condensate therein comprises a fraction corresponding to the heavy ends of the pressure distillate.

It will thus be seen that the invention provides for a partial but regulated condensation of the vapors from the pressure still before the vapors escape to a lower pressure, and that the escape of the vapors is at a constant rate such that regulation thereof is not required. The pressure still can accordingly be operated without the usual pressure control means for regulating the drawing off of vapors or liquid. The regulation is nevertheless effected in a novel and advantageous way within the system itself 95 by variably condensing vapors within the system, and subsequently condensing the fixed amount of vapors that escape from the system.

It will further be seen that, where the 100 pressure still is provided with a reflux tower, the head temperature of the reflux tower can be regulated by the feed so introduced, this regulation being in addition to the regulation effected in the variable condenser. The vapors escaping at the desired head temperature from the top of the reflux tower will be in part condensed in the variable condenser and a fixed amount will escape and be subsequently condensed. The 105 relative amounts of vapors condensed in the variable condenser and in the final condenser can be varied, for example, by varying the size of the fixed orifice and the fixed amount of vapors flowing therethrough. In 110 addition, the amount of vapors condensed in the variable condenser will increase and decrease with the operation of the still, as increased or decreased condensation becomes necessary in maintaining the pressure within the system. When the pressure still is operating normally with but small variations in the amount of vapor formed, a fairly constant amount of condensation will be obtained in the variable condenser, but as 115 the pressure still departs from such normal operation, and the vapors increase or decrease with resulting increase or decrease of pressure, the cooling effect applied to the variable condenser can be correspondingly 120 125 130

varied and an approximately constant pressure maintained.

The invention thus provides a novel method of construction and operation whereby the regulation of the pressure by manipulation of gas or vapor control valves is avoided and whereby the pressure still may be operated with a substantially constant outflow of vapors therefrom, and whereby variations in pressure are taken care of and a substantially uniform pressure obtained by a regulated condensation of vapors within the pressure still system itself and at the same pressure maintained in the pressure still.

The pressure maintained in the pressure still can be varied. With heavier charging stocks such as gas oil, the pressure may be around 90 to 125 pounds, while with lighter charging stocks of the nature of kerosene or light gas oil, considerably higher pressures may be used, e. g. around 300 to 325 pounds, or even much higher. The charging stock for the pressure still may also vary, although the invention is of special advantage in conjunction with pressure stills using heavier charging stock such as gas oil, and where an intermediate cut of the nature of kerosene is to be separated and separately treated. In such a pressure still operating with a heavy charging stock, any lighter constituents introduced with the charging stock can be recovered along with the lighter vapors from the cracking operation, while the introduction of the fresh feed into the top of the reflux tower permits the control of the head temperature of the still independently of the pressure control so that all of the lighter vapors passing over at the regulated head temperature will be obtained in two or more separate fractions due to the fractional condensation, partly under still pressure and partly at lower pressure, to which the vapors are subjected.

Where the charging stock for the pressure still is introduced into the top of the reflux tower, it may contain a considerable amount of light constituents which will be vaporized in the reflux tower and which will pass off from the top of the reflux tower in admixture with the lighter vapors from the cracking operation. These lighter constituents of the feed, in vaporizing in the reflux tower, will add to the refluxing action without increasing the amount of heavier oil entering the still through the reflux tower.

The lighter vapors passing from the top of the reflux tower will be subjected to partial condensation in the variable condenser and the intermediate condensate therefrom will be of a composite character, being made up in part of the constituents produced by the cracking operation and in part of constituents vaporized from the ad-

ditional feed oil. Where the feed oil also contains gasoline or similar light constituents, such constituents will pass to the final condenser with the lighter vapors from the cracking operation so that the pressure distillate recovered will also be of a composite character, containing cracked distillate admixed with the lighter distillate from the feed. The present invention accordingly provides for the recovery of lighter constituents from the feed stock in admixture with the pressure distillate and intermediate distillate or distillates from the cracking operation. The lighter constituents of the feed stock will thus be vaporized in the reflux tower, where they will exert a desirable cooling action, and they will then be fractionally condensed in admixture with the condensates from the pressure still operation.

The present invention enables regulating valves in the vapor lines of pressure stills to be avoided and enables the pressure to be controlled independently of such valves, or, if such valves are used to furnish the fixed orifice, they do not require adjustment during the normal operation of the still. The invention nevertheless permits the final condensation to take place at a lower pressure than that maintained in the still itself. Should excessive pressures develop in the system which the method of control will not take care of, the emergency bypass 31, if of automatic construction, will automatically release the pressure upon a predetermined increase, or, if a hand operated valve is provided, the operator may release the excessive pressure by manipulation of such bypass valve.

I claim:

1. The process of cracking heavier hydrocarbons under pressure, which comprises subjecting the hydrocarbons to a cracking temperature under pressure, subjecting the resulting vapors to a regulated condensation while under pressure, permitting uncondensed vapors to escape through a fixed orifice, and increasing and decreasing the condensation in the said regulated condensation with increase and decrease, respectively, of the pressure.

2. The process of cracking heavier hydrocarbons under pressure, which comprises subjecting the hydrocarbons to a cracking temperature under pressure, subjecting the resulting vapors to a regulated condensation while under pressure, permitting uncondensed vapors to escape through a fixed orifice, and increasing and decreasing the condensation in the said regulated condensation with increase and decrease, respectively, of the rate at which vapors escape through the said orifice.

3. The process of cracking heavier hydrocarbons under pressure, which comprises

- subjecting the hydrocarbons to a cracking temperature under pressure, subjecting the resulting vapors to a regulated condensation while under pressure, withdrawing uncondensed vapors at a substantially uniform rate, and increasing and decreasing the condensation in the said regulated condensation with increase and decrease, respectively, of the pressure.
4. The process of cracking heavier hydrocarbons under pressure, which comprises subjecting the hydrocarbons to a cracking temperature under pressure, subjecting the resulting vapors to a regulated condensation while under pressure, permitting uncondensed vapors to escape through a fixed orifice, and regulating the pressure solely by regulating the said condensation.
5. The process of cracking heavier hydrocarbons under pressure, which comprises subjecting the hydrocarbons to a cracking temperature under pressure, subjecting the resulting vapors to a regulated condensation while under pressure, returning condensate therefrom to the cracking operation, permitting uncondensed vapors to escape through a fixed orifice, and increasing and decreasing the condensation in the said regulated condensation with increase and decrease, respectively, of the pressure.
6. The process of cracking heavier hydrocarbons under pressure, which comprises subjecting the hydrocarbons to a cracking temperature under pressure, subjecting the resulting vapors to a refluxing operation from which reflux is returned to the cracking operation and then to a regulated condensation from which condensate is returned to the cracking operation while under pressure, permitting uncondensed vapors to escape through a fixed orifice, and increasing and decreasing the condensation in the said regulated condensation with increase and decrease, respectively, of the pressure.
7. The process of cracking heavier hydrocarbons under pressure, which comprises subjecting the hydrocarbons to a cracking temperature under pressure, subjecting the resulting vapors to a refluxing operation from which reflux is returned to the cracking operation and then to a regulated condensation while under pressure, permitting uncondensed vapors to escape through a fixed orifice, and increasing and decreasing the condensation in the said regulated condensation with increase and decrease, respectively, of the pressure.
8. The process of cracking heavier hydrocarbons under pressure, which comprises subjecting the hydrocarbons to a cracking temperature under pressure, subjecting the resulting vapors to a regulated condensation while under pressure by heat interchange with feed oil, permitting uncondensed va-
- pors to escape through a fixed orifice, and increasing and decreasing the rate of supply of feed oil with increase and decrease, respectively of the pressure.
9. The process of cracking heavier hydrocarbon oils under pressure, which comprises heating the oils to a cracking temperature, passing the resulting vapors while still under pressure through a condenser, withdrawing vapors and gases from said condenser at a substantially constant rate, passing feed oil in heat-interchanging relation with the vapors in said condenser before introducing it into the pressure still, and increasing and decreasing the rate of flow of the feed oil with increase and decrease in pressure in the system.
10. The process of cracking heavier hydrocarbons under pressure, which comprises subjecting the hydrocarbons to a cracking temperature under pressure, subjecting the resulting vapors to a regulated condensation while under pressure, permitting uncondensed vapors to escape through a fixed orifice, increasing and decreasing the condensation in the said regulated condensation with increase and decrease, respectively, of the pressure, and withdrawing the condensate as a liquid.
11. The process of cracking heavier hydrocarbons under pressure, which comprises subjecting the hydrocarbons to a cracking temperature under pressure, subjecting the resulting vapors to a regulated condensation while under pressure by direct contact with feed oil, permitting uncondensed vapors to escape through a fixed orifice, and increasing and decreasing the supply of feed oil to said condensation with increase and decrease, respectively, of the pressure.
12. Apparatus for the cracking of heavier hydrocarbons under pressure, comprising a pressure still, a condenser communicating with the vapor space of said still, means for withdrawing vapors and gases from the condenser at a substantially constant rate, and means for subjecting the vapors in said condenser to a regulated condensation, said means being automatically actuated by the pressure in said system.
13. Apparatus for the cracking of heavier hydrocarbons under pressure, comprising a pressure still, a reflux tower, and a condenser, all adapted to be maintained under the same pressure, said condenser having a fixed orifice for the discharge therefrom of vapors and gases at a substantially constant rate, means for subjecting the vapors in said condenser to a regulated condensation, and automatic regulating means for regulating the condensation adapted to maintain a substantially constant pressure in the system.
14. Apparatus for the cracking of heavier hydrocarbons under pressure, comprising a pressure still, a reflux tower, and a con-

- 5 denser, all adapted to be maintained under the same pressure, said condenser having a fixed orifice for the discharge therefrom of vapors and gases at a substantially constant rate, means for subjecting the vapors in said condenser to a regulated condensation, and automatic regulating means for regulating the condensation to maintain a substantially constant pressure in the system, said automatic regulating means being controlled by the pressure in the system. 10
- 15 16. Apparatus for the cracking of heavier hydrocarbons under pressure, comprising a pressure still, a reflux tower, and a condenser, all adapted to be maintained under the same pressure, said condenser having a fixed orifice for the discharge therefrom of vapors and gases at a substantially constant rate, means for subjecting the vapors in said condenser to a regulated condensation, and automatic means for regulating the condensation in said condenser, said automatic means being actuated by the pressure in the system. 20
- 25 17. Apparatus for the cracking of heavier hydrocarbons under pressure, comprising a pressure still, a condenser communicating with the vapor space of said still, means for flowing feed oil to the still in heat inter-
30 change with vapors in the said condenser, means for withdrawing vapors and gases from the condenser at a substantially constant rate, and means actuated by the pressure in said system for increasing and de-
35 creasing the flow of feed oil with increase and decrease, respectively, of the pressure. 40
18. Apparatus for the cracking of heavier hydrocarbons, comprising a system adapted to be maintained under pressure including means for heating the hydrocarbons to a cracking temperature therein, a condenser communicating with said system and adapted to be maintained under substantially the same pressure, means for withdrawing vapors and gases from the condenser at a substantially constant rate, and means actuated by the pressure in the system for increasing and decreasing condensation in the condenser with increase and decrease, respectively, of the pressure. 45
- 50 19. Apparatus for the cracking of heavier hydrocarbons, comprising a system adapted to be maintained under pressure including means for heating the hydrocarbons to a cracking temperature therein, a condenser communicating with said system and adapted to be maintained under substantially the same pressure, means for withdrawing vapors and gases from the condenser at a substantially constant rate, means for flowing feed oil to the system in heat exchange with vapors in the condenser, and means actuated by the pressure in the system for increasing and decreasing the flow of feed oil with increase and decrease, respectively, 55 of the pressure. 60
